UNITED STATES PATENT OFFICE.

FRANK BENJAMIN HARRISON, OF TOLEDO, OHIO.

DUST-GUARD.

SPECIFICATION forming part of Letters Patent No. 752,164, dated February 16, 1904.

Application filed June 25, 1903. Serial No. 163,032. (No model.)

To all whom it may concern:

Be it known that I, FRANK BENJAMIN HARRISON, a citizen of the United States, residing at Toledo, in the county of Lucas and State of Ohio, have invented new and useful Improvements in Dust-Guards for Car Journal-Boxes, of which the following is a specification.

The object of my invention is the production of a dust-guard for journal-boxes which shall effectively exclude dust, sand, and other foreign matter from the interior of the box and likewise prevent the escape of oil therefrom, which shall be comparatively simple in construction, cheap in first cost and durable, which will retain its proper position within the chamber of the box when the brass wears away, which will not become deranged by any cause whatever in practical service, and which withal shall possess such desirable features and characteristics as will constitute it a superior means for performing the desired functions.

With the above ends in view my invention consists in certain novelties of construction and combinations and arrangements of parts, as hereinafter set forth and claimed.

The accompanying drawings illustrate an example and a modification of the physical embodiment of my invention constructed according to the best mode I have so far devised for the practical application of the principle.

Figure 1 shows in dotted lines a journal-box and a journal and in full lines my dust-guard in operative position, the box and guard being in section, so as to clearly disclose the relative positions of the several parts. Fig. 2 is a side view of the guard removed from the dust-guard chamber and enlarged. Fig. 3 is a view similar to Fig. 2, the halves of the frame being separated to show the tongue upon the upper half of the frame and the pins which retain the two halves in their proper positions. Fig. 4 is a section of a pin and the ring, taken on line α of Fig. 3. Fig. 5 shows the modification.

Referring to the several figures, the numeral 1 designates a journal-box, such as is in common use in connection with car-trucks; 2, the dust-guard chamber, open at the top, as usual;

3, an axle-journal, and 4 the dust-guard bearing of the axle.

The dust-guard is inserted at the top opening of the chamber and is located when in use as shown in Fig. 1. 55

The numeral 5 designates the upper half of the frame of the guard; 6, a semicircular tongue; 7, holes in the guard at the terminations of the tongue on each side of the upper part of the frame; 8, the lower half of the frame; 9, the semicircular tongue upon the lower half of the frame; 10, the pins rigidly secured to the lower half of the frame and the free ends located within the holes 7 of the upper half; 11, the metallic ring, U-shaped in cross-section, acting as a spring; 12, 13, the lapped free ends of the ring, and 14 is a wedge inserted in the opening of the dust-guard chamber to exclude dust and other foreign matter. 70

It will be observed that the tongue upon the parts of the frame is of the greatest possible thickness and slightly less than the thickness of the wood or other material constituting the frame, so as to be of great strength and to afford ample wearing material. The spring-ring is designed to frictionally engage the dust-guard bearing of the journal and to revolve with it, and to allow the ring to expand slightly the diameter of the same is less than the 80 diametrical distance between the edges of the tongue. When the ring is in position, the outer parallel surfaces of the ring are in the same planes as the surfaces of the two parts of the frame, so that its outer surfaces will 85 not wear excessively by contact with the inner surfaces of the dust-guard chamber.

The lapped free ends should in practice be so shaped that there will not be any open space between the ring and the journal for the passage of dust. In some cases I may make the ring integral and the flanges lapping over the edges of the frame. 90

In Fig. 5 is illustrated a modification. Upon the tongues 9 and 6 of the two sections of the frame is placed a U-shaped metallic ring 15, which frictionally engages the tongue and which is not designed to revolve. The ring 11 loosely fits the ring 15 and turns upon it. This arrangement provides a metallic bear- 95

ing-surface for ring 11, which will be more durable than the tongue which directly receives the ring 11 in the main example.

From the foregoing description, taken in connection with the drawings, it becomes obvious that I have produced a dust-guard which fulfills all the conditions set forth as the purpose of my invention.

While I have specifically illustrated only one example and a modification of the physical embodiment of my invention, I do not thereby intend to limit the scope thereof to such example and modification, inasmuch as in practice colorable changes and modifications may be introduced without constituting substantial departures.

What I claim as new, and desire to secure by Letters Patent, is—

1. The combination with a journal and a journal-box having a dust-guard chamber, of a frame with a circular opening therein, and a ring U-shaped in cross-section with its edges loosely lapping over the circular edge of the frame and frictionally engaging the dust-guard bearing of the axle so as to revolve with the journal.

2. The combination with a journal, and a journal-box having a dust-guard chamber, of a frame with a circular opening therein, and a spring-ring U-shaped in cross-section with its ends breaking joints when in position within the circular opening of the frame and its edges lapping over the circular edge of the frame and loosely engaging the same.

3. The combination with a journal and journal-box having a dust-guard chamber, of a frame made in sections with a circular opening, and a ring U-shaped in cross-section with

its edges lapping over the edges of the sections of the frame and loosely engaging the same so that the ring may revolve with the journal.

4. The combination with a journal and a journal-box having a dust-guard chamber, of a frame provided with a circular opening with a tongue, and a ring U-shaped in cross-section and loosely engaging the tongue and frictionally engaging the dust-guard bearing of the axle so as to revolve with the journal.

5. The combination with a journal and a journal-box having a dust-guard chamber, of a frame having a circular opening with a tongue and a spring-ring U-shaped in cross-section with free ends which overlap, said ring frictionally engaging the dust-guard bearing of the axle and loosely engaging the tongue of the frame.

6. A sectional dust-guard frame having a substantially circular opening and a ring U-shaped in cross-section loosely overlapping the edges of the opening and fixed upon the dust-guard bearing of the axle so as to revolve with the journal.

7. A dust-guard frame having a substantially circular opening, a ring U-shaped in cross-section surrounding the opening, and a second ring U-shaped in cross-section overlapping the first-mentioned ring U-shaped in cross-section and adapted to revolve in frictional contact therewith.

In testimony whereof I affix my signature in presence of two witnesses.

FRANK BENJAMIN HARRISON.
